B. A. TERLINDE
TOWEL HOLDER

Des. 159,018

Filed Sept. 20, 1947

FIG. 1

FIG. 2

Inventor

BERNARD A. TERLINDE

By

Robert M. Dunning

UNITED STATES PATENT OFFICE

159,018

TOWEL HOLDER

Bernard A. Terlinde, White Bear, Minn.

Application September 20, 1947, Serial No. 141,513

Term of patent 3½ years

(Cl. D4—3)

Be it known that I, Bernard A. Terlinde, a citizen of the United States, residing at White Bear, county of Ramsey, and State of Minnesota, have invented a new, original, and ornamental Design for Towel Holder, of which the following is a specification, reference being had to the accompanying drawing, forming part thereof.

I claim:

The ornamental design for a towel holder, as shown.

BERNARD A. TERLINDE.
